UNITED STATES PATENT OFFICE.

WILLIAM F. MARTIN, OF WORMLEYSBURG, PENNSYLVANIA.

COAL SCREENING AND WASHING MACHINE.

Application filed May 18, 1922. Serial No. 561,981.

To all whom it may concern:

Be it known that I, WILLIAM F. MARTIN, a citizen of the United States, residing at Wormleysburg, in the county of Dauphin 5 and State of Pennsylvania, have invented certain new and useful Improvements in Coal Screening and Washing Machines; and I do declare the following to be a full, clear, and exact description of the invention, such 10 as will enable others skilled in the art to which it appertains to make and use the same.

My invention relates to improvements in machines for cleaning and washing ore and 15 the like and has reference more particularly to machines of the character employing a plurality of pockets beneath a screen for receiving waste material passing through said screen.

20 The object of the present invention is to provide an improved arrangement of valves for controlling discharge of the waste material from the collecting pockets.

In carrying out the above end, a further 25 aim is to provide novel means whereby the valves may be repeatedly opened and closed by power-operated means, preferably driven by a water wheel.

With the foregoing in view, the invention 30 resides in the novel subject matter hereinafter described and claimed, the description being supplemented by the accompanying drawings.

Figure 1 is a side elevation partly broken 35 away and in section, showing a machine constructed in accordance with my invention.

Figure 2 is a longitudinal sectional view showing a somewhat different arrangement 40 of valves.

Figure 3 is a vertical transverse sectional view as indicated by line 3—3 of Fig. 2.

Figure 4 is a duplicate of Fig. 2 with the exception that it illustrates a different form 45 of collecting pocket.

In the drawings above briefly described, the numeral 1 designates a suitably inclined frame within which is secured an appropriate screen 2. Beneath this screen, the 50 frame is provided with a plurality of pockets 3 adapted to receive the waste material passing through the screen. In Figs. 1 and 2, the pockets 3 are provided with straight sides 4 which converge downwardly, while in Fig. 4, the opposed sides of said pockets are curved as indicated by the numeral 4a.

In both instances, a gap 5 is left between the lower edges of the side walls through which the contents of the pockets are adapted to discharge. For controlling these gaps or outlets, I employ a plurality of sliding valve plates 6 which may be supported in any preferred manner, for instance by angle iron tracks 7 secured to the sides of the frame 1. The several valve plates 6 are secured to a 60 longitudinal connecting rod 8 which may be moved either by hand or by power to control the valves. I prefer however to connect the rod 8 with a depending crank arm 9 on a transverse rock shaft 10 by means of a 65 link or the like 11, said rock shaft being appropriately mounted at one end of the frame and having a crank arm 12 adapted to be operated by power. In the present showing, a pitman rod 13 is connected adjustably or otherwise with the arm 12 and if desired the length of said pitman rod may be adjustable, for instance by means of a 70 turn-buckle 14. In the present showing, the rod 13 has suitable connection with an eccentric 75 15 on the shaft 16 of a water wheel 17, the latter being located beneath the discharge spout 18 onto which water from the inclined bottom 19 of the frame 1, is discharged. The shaft 16 may be suitably 80 supported and I have shown U-shaped hang- 85 ers 20 for this purpose.

By the construction described, it will be seen that rotation of the water wheel 17 will cause stroking of the pitman 13, thereby 90 oscillating the shaft 10 and producing a reciprocating motion of the connecting rod 8, the result being that the valves 6 are alternately opened and closed and it will be seen that whenever said valves open, the waste 95 material which has accumulated in the pockets 3 will be discharged therefrom. The valves may be arranged on the connecting rod 8 so as to open and close in unison, as will be clear from Figs. 1 and 4, or the arrangement may be such that the valves will open successively and close in reverse order, (see Fig. 2). In all forms of construction, the machine is simple yet efficient and reliable and hence I prefer to employ the details 100 shown. It is to be understood however that within the scope of the invention as claimed, numerous minor changes may be made.

I claim:

1. The combination of a frame, a screen 110 in said frame, collecting pockets in the frame beneath the screen, said pockets hav-

ing outlet openings, valves normally closing said outlet openings, a connecting rod associated with said valves and movable longitudinally for producing simultaneous movement thereof, a rotary drive element, and means for converting rotary movement of said drive element into reciprocating movement for said rod.

2. A screening machine comprising a frame, a screen therein, a plurality of collecting pockets in the frame beneath the screen, each pocket having an outlet opening in its bottom, slide valves under said pockets for controlling said openings, guiding means for said slide valves carried by the frame, a longitudinally extending connecting bar connected with all of said slide valves, a water wheel turned by water passing from said frame, and means actuated by said water wheel for shifting said connecting bar to simultaneously move said valves.

3. A screening machine comprising a frame, a screen in said frame upon which material and water are adapted to be delivered, pockets in the frame beneath said screen, each pocket having an outlet opening, valves for controlling the outlet openings of said pockets, a water wheel driven by the water supplied to the screening machine, and connecting means between said water wheel and said valves for alternately opening and closing the latter.

4. A screening machine comprising a

frame, a screen in said frame upon which material and water are adapted to be delivered, pockets in the frame beneath said screen, each pocket having an outlet opening, slide valves for controlling the outlets of said pockets, a connecting rod connected with said slide valves, a water wheel driven by the water supplied to the screening machine, and connecting means between said connecting rod and said water wheel for reciprocating the former by means of the latter.

5. A screening machine comprising a frame, a screen in said frame upon which material and water are adapted to be delivered, pockets in the frame beneath said screen, each pocket having an outlet opening, slide valves for controlling the outlet openings of said pockets, a longitudinal connecting rod connected with said slide valves, a transverse rock shaft mounted on the frame and having an eccentric connected with said connecting rod, a crank arm on said rock shaft, a pitman connected with said crank arm, and a water wheel having an eccentric connected with said pitman, said water wheel being positioned to be operated by the water supplied to the screening machine.

In testimony whereof I have hereunto set my hand.

WILLIAM F. MARTIN.
